UNITED STATES PATENT OFFICE.

LESLIE I. ZIEGLER, OF INDIANAPOLIS, INDIANA, ASSIGNOR TO NORDYKE & MARMON COMPANY, OF INDIANAPOLIS, INDIANA, A CORPORATION OF INDIANA.

FEEDER.

1,427,341.

Specification of Letters Patent. Patented Aug. 29, 1922.

Application filed August 12, 1920. Serial No. 403,105.

To all whom it may concern:

Be it known that I, LESLIE I. ZIEGLER, a citizen of the United States, residing at Indianapolis, in the county of Marion and State of Indiana, have invented a new and useful Feeder, of which the following is a specification.

The object of my invention is to provide an improved feeding apparatus for grinding rolls, or other similar uses, where a laterally uniformly distributed stream of material of automatically varying volume, depending upon the rate of supply, is desired.

15 The accompanying drawings illustrate my invention.

Figure 1 is a vertical section and Fig. 2 a side elevation, with the front removed.

In the drawings, 10 indicates a main casing in which is arranged a downwardly-inclined metal chute 11, curved near its lower edge to closely approximate the lower part of the feed roll 12 which is rotated continuously in the direction indicated by the arrow. The extreme lower edge of plate 11, as indicated at 13, is projected downwardly and forwardly to form an opening to bridge the gap between roll 12 and a guide pan 14, which is adjustably held in casing 10 by means of clamping bolts 15 passing through slots 16 in the sides of pan 14 and through the adjacent walls of casing 10.

Journaled in suitable brackets 20 in the upper part of casing 10 is a rock shaft 21 provided with arms 22 which carry, at their outer ends, a cross bar 23, upon the ends of which are pivoted the slotted retaining links 24 which may be clamped in desired adjusted position by clamping nuts 25 on the bolts 26 which pass through the walls of casing 10 and the slots of retaining links 24. Pivoted upon cross bar 23 are two depending arms 30, the lower ends of which are carried by bolts 31 upon which is secured 45 the gage plate 32.

Heretofore, it has been common in structures of this general type to provide a gage plate which has substantially a plain surface, but I have found in practice that much greater uniformity of lateral spreading of the grain is obtained by providing an in-turned toe or lower edge on gage plate 32, as indicated at 32'.

Arranged near the lower edge of the gage plate 32 is a rock shaft 40 journaled in the

casing 10 and provided at its ends with arms 41 carrying weights 42. Secured to shaft 40 are pressure arms 43, 43, each of which is provided with a temper screw 44 adapted to engage and press upon the gage plate 32 at a point between shaft 40 and bar 23.

Threaded through suitable brackets 45 on casing 10 are stop screws 46 arranged to be engaged by gage plate 32 so as to limit the outward throw of said gage plate.

Swinging loosely upon shaft 40 are two arms 47 which carry a baffle plate 48 at their lower ends, said baffle plate being projected into the mouth of pan 14 at nearly a right angle. Pan 14 is provided with an upper plate 14' which is parallel with and spaced from the bottom of the pan.

Pan 14 delivers downwardly to the carriage between the rolls or other feed point (not shown).

In operation, a stream of material is delivered into the hopper, or throat, formed by the elements 11, 12 and 32 and element 12 is rotated in a direction indicated by the arrow. As the supply stream increases or diminishes, the pressure of the accumulated material against the gage plate 32 varies and weight 42 yields more or less under this pressure, so that the delivery throat between roll 12 and the toe 32' of gage plate 32, moves automatically toward or from roll 12 as the accumulation of material in the hopper decreases or increases.

The gage plate 32 also serves to spread the material lengthwise of the roller and, as the stream is projected downwardly by the roller from beneath the gage plate, it strikes the baffle 48 and by it is spread upon pan 14; the various parts cooperating to provide an evenly distributed stream of material to the pan 14, the depth of this stream varying automatically as the inflow of material varies.

I claim as my invention:

1. A feeder comprising an inclined hopper wall, a rotatable drum arranged in conjunction with the lower part of said wall, a gage plate associated with said drum in opposition to the hopper wall and provided with a lower edge lying at a greater angle to the roller than the upper part of the gage plate, means for pivotally suspending said gage plate, means for vertically adjusting the suspension means, a rock shaft arranged materially below the suspension means, a

pressure arm carried by the rock shaft and engaging the gage plate to urge it toward the roller, yielding means for holding said pressure arm in contact with the gage plate, 5 and a baffle plate suspended in the line of delivery from the roller.

2. A feeder comprising an inclined hopper wall, a rotatable drum arranged in conjunction with the lower part of said wall, 10 a gage plate associated with said drum in opposition to the hopper wall, means for pivotally suspending said gage plate, means for vertically adjusting the suspension means, a rock shaft arranged materially below the 15 suspension means, a pressure arm carried by the rock shaft and engaging the gage plate to urge it toward the roller, yielding means for holding said pressure arm in contact with the gage plate, and a baffle plate suspended in the line of delivery from the roller.

3. A feeder comprising an inclined hopper wall, a rotatable drum arranged in conjunction with the lower part of said wall, a gage plate associated with said drum in opposition to the hopper wall and provided with a 20 lower edge lying at a greater angle to the roller than the upper part of the gage plate,

means for pivotally suspending said gage plate, means for vertically adjusting the suspension means, a rock shaft, a pressure arm 30 carried by the rock shaft and engaging the gage plate to urge it toward the roller, yielding means for holding said pressure arm in contact with the gage plate, and a baffle plate suspended in the line of delivery from the 35 roller.

4. A feeder comprising an inclined hopper wall, a rotatable drum arranged in conjunction with the lower part of said wall, a gage plate associated with said drum in opposition to the hopper wall, means for pivotally suspending said gage plate, means for vertically adjusting the suspension means, a rock shaft, a pressure arm carried by the rock 40 shaft and engaging the gage plate to urge it toward the roller, yielding means for holding said pressure arm in contact with the gage plate, and a baffle plate suspended in the line of delivery from the roller.

In witness whereof, I have hereunto set 50 my hand at Indianapolis, Indiana, this 10th day of August, A. D. one thousand nine hundred and twenty.

LESLIE I. ZIEGLER.
